NET HAT COVERING

Ruth F. Emmet, New York, N.Y., and Katherine M. Laster, Dover, Del., assignors to International Latex Corporation, Dover, Del., a corporation of Delaware

Filed Dec. 6, 1963, Ser. No. 77,704

Term of patent 14 years

(Cl. D3—13)

FIG. 1.

FIG. 2.

FIG. 3.

The dominant feature of the design resides in a net hat covering having on the outer surface thereof a series of relatively closely spaced, scalloped, double ruffles spirally attached to the hat covering to provide it with a pompon-like effect as shown.

We claim:

The ornamental design for a net hat covering as shown and described.
